BACON GRID

Anthony L. Fink, San Diego, Calif.

Application June 1, 1954, Serial No. 30,757

Term of patent 14 years

(Cl. D44—1)

Fig. 1

Fig. 2

Fig. 3

To all whom it may concern:

Be it known that I, Anthony L. Fink, a citizen of the United States and a resident of San Diego, in the county of San Diego and State of California, have invented a new, original, and ornamental Design for a Bacon Grid, of which the following is a specification, reference being had to the accompanying drawing, forming a part thereof, and wherein:

Figure 1 is a perspective view of a bacon grid, showing my new design;

Figure 2 is a top plan view thereof; and

Figure 3 is a side elevational view thereof.

I claim:

The ornamental design for a bacon grid, as shown.
